UNITED STATES PATENT OFFICE

2,037,725

ROTARY EMBROIDERING MACHINE

Charles A. Kaiser, Philadelphia, Pa.

Application October 20, 1932, Serial No. 638,706

11 Claims. (Cl. 112—79)

The object of this invention is to devise a novel construction of a rotary embroidering machine.

A further object of the invention is to devise a novel embroidering machine wherein novel means are provided for forming the loops for placing a tension on the yarn or thread during the formation of the loops and novel means for holding a loop as the yarn or thread is being drawn during the upward movement of the needle.

10 A further object is to devise a novel work holder and novel means for adjusting it together with novel means for placing a tension on it during the embroidering operation.

With the above and other objects in view, as will hereinafter more clearly appear, my invention comprehends a novel embroidering machine having a reciprocatory yarn carrying needle, novel tension mechanism, novel means for retaining a loop during the drawing of the yarn, and 20 novel controlling mechanism for controlling the cyclical operation of the machine.

It further comprehends a novel automatic tension device for the yarn passing to the needle.

It further comprehends novel means for moving the loops which have been formed out of the path of the needle.

It further comprehends a novel construction and arrangement of fabric feeding mechanism.

Other novel features of construction and advantage will hereinafter more clearly appear in the detailed description and the appended claims.

For the purpose of illustrating the invention I have shown in the accompanying drawings a typical embodiment of it, which, in practice, will give satisfactory and reliable results. It is, however, to be understood that the various instrumentalities of which my invention consists can be variously arranged and organized, and my invention is not limited to the exact arrangement and organization of these instrumentalities as herein set forth.

Figure 1 is a sectional elevation of an embroidering machine embodying my invention.

Figure 2 is an exploded view of a tension device employed.

Figure 3 is a front elevation of the tension device showing it in the position it assumes when holding the yarn.

50 Figure 4 is a front elevation of the tension device and a portion of the needle bar, showing the position the parts assume when the yarn is released.

Figure 5 is a perspective view of a compound cam employed and parts controlled thereby.

Figure 6 is a front elevation, partly broken away, for the sake of clearness of illustration.

Figure 7 is a transverse section, showing more clearly the relation between certain of the parts.

Figure 8 is a perspective view, showing certain 5 of the driving parts seen in Figure 7.

Figure 9 is a perspective view of the machine, showing more particularly the work frame and the manner in which it is adjusted.

Figure 10 is a section on line 10—10 of Figure 14, showing more particularly the work carrier and its adjuncts.

Figure 11 is a section on line 11—11 of Figure 14.

Figure 12 is a perspective view, showing more 15 particularly the manner in which a manually releasable mechanism can be employed for the feed of the work table.

Figure 13 is a detailed section of a portion of the construction seen in Figure 10.

Figure 14 is a perspective view of a portion of 20 the work table and its feeding mechanism.

Figure 15 is a section taken substantially on line 15—15 of Figure 11.

Figure 16 is a perspective view, showing more 25 particularly the yarn being drawn down by the needle.

Figure 17 is a perspective view, showing more 30 particularly the manner in which the hook cooperates with the yarn carried by the needle.

Figure 18 is a perspective view of a hook carrier, and a cam operated slide and certain of their adjuncts.

Figure 19 is a sectional detail showing the needle and hook in positions they assume during the 35 operation.

Figure 20 is a view similar to Figure 19 but showing the parts in different relation from that seen in Figure 19.

Figure 21 is a sectional detail, showing more 40 clearly, the manner in which preformed loops are moved out of the path of the needle.

Figure 22 is a sectional detail, showing more 45 particularly a portion of the fabric feeding mechanism.

Similar numerals of reference indicate corresponding parts.

Referring to the drawings:

1 designates the frame of the machine, the construction and contour of which may vary widely 50 in practice. 2 designates the main driving shaft which is operatively connected with an electric or other motor, in any desired manner, to be driven thereby. The shaft 2 is provided with a sprocket wheel 3 around which passes a sprocket chain 4 55

which latter also passes around a sprocket wheel 5 fixed to a shaft 6 journalled in the machine frame. The shaft 6 has connected with it in any desired or conventional manner but eccentrically thereto, a driving arm 7, the free end of which is pivotally connected to the reciprocatory needle bar 8, which latter carries the needle 9. The needle bar is guided in any conventional manner in the head of the machine frame. 10 designates a presser foot carried by a rod passing through guides 11 and having a spring 12 which tends to move it downwardly and retain it in its downward position. The presser foot is connected by a pin and slot connection with a link 13 connected to an eccentric 14 having a grasping handle 15 whereby the presser foot can be raised and retained in such raised position.

The automatic yarn tensioning mechanism

20 The yarn 16, see Figure 9, passes from the cop 17 through suitable guides to a yarn tensioning device 18 of any desired or conventional construction, and, as shown in Figure 6, this consists of the conventional discs with a spring tending to move one towards the other. The yarn then passes to the automatic yarn clamping mechanism 19 which will now be described, reference being directed more particularly to Figures 1, 2, 3, 4 and 6. 20 designates a bar secured to the head of the frame 1 at opposite ends and on this bar is adjustably secured a block 21 having a rounded corner at its lower portion. This block is fixed in its adjusted position by means of a fastening device 22. The needle bar 8 passes through an apertured block 23 which is fixed to it by means of a set screw 24. This block carries a yarn guide 25. Secured to the bottom of the block 23 by means of suitable fastening devices, is the rearwardly extending flange 26 of a bracket 27, the flange 26 is apertured as at 28 to permit the needle bar 8 to pass therethrough. The free ends of the bracket 27 are deflected at right angles and apertured to receive a pivot pin 29 which passes through an apertured member 30 having its rear end rounded as at 31. A yarn stop member in the form of a plate 32 is secured to the member 30 by means of fastening devices 33, certain of which also serve to secure to the member 30 a curved strip 34 which, during the upward movement of the needle bar 8, engages the cam member formed by the block 21 thus moving the yarn contacting member 32 out of engagement with the yarn and opposing the action of the spring plate 35. The spring plate 35 is in the form of a strip of spring metal having one end secured to the flange 26 by means of a fastening device 36. The free end of the spring presses against the member 30 as will be clearly understood by reference to Figures 3 and 4, so that the tendency of this spring is to cause the yarn clamping member 32 to clamp the yarn against the block 23 except when it is moved into unclamped position, as seen in Figure 4.

Fabric feeding mechanism

65 The main driving shaft 2 has fixed to it an eccentric 37 which drives a connecting rod 38, the free end of which is connected with a rod 39 passing through offset arms of a rock shaft 40 which is tubular and mounted on a bearing rod 41 carried by bearings 42, see Figure 7. The shaft 39 has mounted on it one end of a reciprocatory bar 43 having its forward end bifurcated as at 44. 45 designates the fabric feed having the downwardly deflected flange 46 which is connected at

47 to the reciprocatory bar 43, see more particularly Figure 22. During the reciprocation of the fabric feed 45 it is given an up and down movement which will now be described. Referring now to Figure 8, it will be seen that the main driving shaft 2 has fixed to it an eccentric 48 which actuates a connecting rod 49, the forward end of which is provided with a pin 50 which extends into a slot 51 of a link 52 fixed to a cam shaft 53 journalled in bearings 54. The shaft 10 53 has fixed to it a cam 55 positioned in the bifurcated end 44 of the reciprocatory bar 43 so that the forward end of this bar is moved upwardly and downwardly during the reciprocation of such bar as will be hereinafter fully explained. 15

Loop controlling mechanism

The shaft 2 has fixed to its free end a compound cam 56 having a cam surface 57 and a dwell 58 and a cam surface 59 which forms a continuation of a dwell 60. The frame 1 has a downward extension 61, see Figure 1, to which is secured a bracket 62 by means of fastening devices 63. The bracket 62 has pivotally mounted in it a hook carrier 64 as at 65. The lower end of the hook carrier is provided with a pin 66 which extends into the bifurcated end 67 of a bar 68 slidable in the downward extension 61. The bar 68 has a reduced end which carries a spring 69 interposed between a fastening device 70, at the free end of the bar 68 and a washer 71, which bears against said downward extension 61. The bar 68 carries a roller 72 which cooperates with the cam face 59 and the dwell 60 of the compound cam 56, see Figure 5. The hook carrier 64 has at its upper end a laterally extending curved hook 73. The hook carrier 64 has mounted on it a reciprocatory slide 74, see Figure 18, having rollers 75 between which is disposed a cam 76 to effect the reciprocatory movement of the slide 74. The cam 76 is fixed to the main drive shaft 2. The upper end of the slide 74 is recessed, as at 77, to receive a working tool, such as, for example, a punch which will form holes in the fabric through which the needle will pass or for cutting purposes.

The cam face 57 and dwell 58 cooperate with a roller 78 carried by a binder bar 79 which has connected to it one end of a spring 80, see Figure 1, the opposite end of said spring being connected to a fixed point of the frame. This binder bar 79 has its forward end adapted to bind or clamp the thread against the shoulder 81, see more particularly Figure 20, during a stage of the operation, the frame being recessed as shown in Figures 19 and 20, and the binder bar having an offset portion movably mounted in such recess portion. This binder bar cooperates with suitable guides on the machine frame, as shown at 82.

The work tensioning device

I provide means to place a desired tension on the fabric during the embroidering operation. The shaft 2, see Figure 1, is provided with a gear 65 83 which meshes with a gear 84 on a shaft 85 suitably journalled on the machine frame. This shaft is provided with a friction coupling 86 of any desired or conventional construction. The shaft 85 has connected with it by means of a flexible 70 joint 87, a knurled roller 88 disposed at an angle to the shaft 85. The presser foot 10 is provided with a spring 89 which presses the fabric which is being embroidered against the knurled roller 88.

The work frame and its controlling mechanism

The fabric 90 which is to be embroidered, see Figure 9, is secured in any desired manner to a frame 91. This frame is mounted for relative rotation and movement towards the needle on a table 92 having upwardly projecting pins 93 to pass through the fabric. A disc 94 having the knurled apertured hubs 95 to fit over the pins 93 serves as a means for retaining the work frame on the table 92 which is provided with a stem 96, rotatably mounted in a bar 97, secured to the machine frame in any desired manner so as to be relatively movable therewith. The stem 96 is provided with a groove 98 into which is adapted to extend a locking member 99 carried by a flat spring 100, one end of which is fixed in any desired manner to the support 97. The spring 100 has fixed to its free end a wire 101 in order that it can be manually actuated to effect the release of the stem 96 so that the work and work holder can be removed as a unit from the machine when desired. The support 97 has fixed to it a block 102 recessed to receive a stationary bar 103 having at its outer side the projecting pins 104. The top of the bar is provided with recesses 105 into which is adapted to extend a locking member 106 carried by the free end of a spring 107 the opposite end of which is fixed to the block 102 by means of a fastening device 108, see Figure 10. 109 designates a block having a recess 110 forming a clearance for the pins 104, see Figure 14. This block 109 is secured to the block 102 in spaced relationship thereto by means of fastening devices 111 so that the work support 97 is slidably mounted on the stationary bar 103. The block 109 has rotatably mounted on it a star wheel 112 having four arms radiating from it adapted to engage the pins 104. This star wheel 112 is provided with a grasping handle 113. The block 109 is provided with a recess 114 to receive the star wheel.

I provide means for retaining the preformed loops out of the path of the needle. The main driving shaft 2, see Figure 7, has fixed thereto a sprocket wheel 115 around which passes a sprocket 116 which also passes around a sprocket wheel 117 fixed to a lay shaft 118 suitably mounted on the machine frame. The shaft 118 is intergeared at 119 with a shaft 120 which carries a rotary brush 121. This brush 121 extends through an opening 122 in the table or bed 123 and brushing against the loops of the fabric 90 retains them out of the path of the needle as is apparent.

The operation will now be apparent to those skilled in this art and is as follows.

The fabric 90 is secured to the work frame 91 and mounted on the work holder 92 so that the embroidery may start at the central portion of the fabric and may be formed outwardly to the outer portions of the fabric. The presser foot 10 is moved downwardly and the spring 89 causes the fabric to engage the tension roll 88. The machine is now ready for embroidering. As the main driving shaft 2 revolves it will be apparent that the shaft 6 will be driven by the sprocket chain 4 and a reciprocatory movement will be imparted to the needle 9. The needle 9 passes downwardly through the fabric and the compound cam 56 causes the bar 68, see Figure 5, to move forwardly, see also Figures 19 and 20, so that the hook 13 will pass through the loop moving from the position seen in Figure 19 to that seen in Figure 20. The needle 9 now moves upwardly with the loop retained on the hook 13.

As the needle moves upwardly the cam 56 causes the forward movement of the binder or clamping bar 79 so that the yarn is clamped against the shoulder 81, see Figure 20. As soon as the strip 34 engages the cam member 21 the tension device will be released so that sufficient yarn can be drawn from the bobbin or cop 17 for the formation for the proper length of loop. As the needle 9 again moves downwardly the yarn clamping member 32 will bind the yarn as soon as the strip 34 passes out of engagement with the cam member 21 due to the action of the spring 35. The yarn is clamped all of the time except when the needle bar is going over dead center, at which time the feed of the fabric takes place. After each loop the fabric is advanced one step by the action of the fabric feeding member 45 which, as is apparent, from Figure 8 and the description already given, moves upwardly and forwardly to advance the fabric and then moves downwardly and rearwardly. The knurled tension roll 88 which is continuously driven places a slight tension or stretch on the fabric during the embroidery operation. The slide 74 is moved upwardly and downwardly by the cam 76 and in case a heavy fabric is being embroidered a punch may be connected to the slide to form holes in the fabric for the needle. As the needle moves upwardly the hook carrier 64 is moved rearwardly by the spring 69 into the position seen in Figure 19 ready for the next course.

In this manner any desired length of loop may be formed on one side of the fabric. When the embroidery is completed the work frame is removed from the machine and from the work support. After each course the work frame is advanced one step by actuating the handle 113 to cause the star wheel 112 to engage the pins 104.

It will now be apparent that I have devised a new and useful rotary embroidering machine 40 which embodies the features of advantage enumerated as desirable in the statement of the invention and the above description, and while I have, in the present instance, shown and described a preferred embodiment thereof which 45 will give in practice satisfactory and reliable results, it is to be understood that this embodiment is susceptible of modification in various particulars without departing from the spirit or scope of the invention or sacrificing any of its advantages.

Having thus described my invention what I claim as new and desire to secure by Letters Patent, is:—

1. In an embroidering machine, a reciprocatory 55 needle bar, a needle carried thereby to receive the yarn, a hook operative to retain a loop beneath the fabric being embroidered, an automatic clamping device for the yarn controlled by the movement of said needle bar, means to clamp the yarn during the upward movement of the needle, and means to oscillate said hook.

2. In an embroidering machine, a main driving shaft, a needle bar and its needle reciprocated thereby, an oscillating hook cooperating with the 65 yarn carried by the needle to form a loop, a yarn clamp operative to clamp the yarn after the formation of the loop, cam means actuated by said driving shaft to oscillate said hook and to reciprocate said yarn clamp, and an automatic yarn 70 clamping device controlled by the needle bar to determine the length of yarn withdrawn for the formation of a loop.

3. In an embroidering machine, a main driving shaft, a needle bar and its needle reciprocated 75

thereby, an oscillating hook cooperating with the yarn carried by the needle to retain a loop, a reciprocatory yarn clamp operative to clamp the yarn in proximity to the needle after the formation of the loop, cam means actuated by said driving shaft to oscillate said hook and to reciprocate said yarn clamp, and an automatic clamping device to determine the length of yarn withdrawn for the formation of a loop, said clamping device being adjustable to vary the length of yarn withdrawn for the formation of a loop and being unclamped by the movement of the needle bar.

4. In an embroidering machine, a main driving shaft, a needle bar and its needle reciprocated thereby, cam means on said driving shaft, a hook carrier oscillated by said means to form a loop and retain it during the upward movement of the needle, a slide on said hook carrier and reciprocated by said cam means, and a reciprocatory yarn clamp also actuated by said cam means.

5. In an embroidering machine, a main driving shaft, a needle bar and its needle reciprocated thereby, a compound cam driven by said shaft, a hook having yarn engaging movements controlled by said cam and effective to center a loop in the yarn, a yarn clamp controlled by said cam to clamp the yarn after a loop has been formed, and an automatic yarn clamping device which is in clamped condition during the downward movement of the needle bar and which is automatically unclamped after a predetermined upward travel of the needle bar.

6. In an embroidering machine, a reciprocatory needle adapted to carry the yarn, a rotary work support, means to rotate said support, loop forming and retaining mechanism to form a loop of a definite length, and means to move pre-formed loops out of the path of said needle.

7. In an embroidering machine, a needle bar and its needle, a block adjustably carried by said needle bar, a yarn clamping member pivotally supported on said needle bar to clamp the yarn against said block, a spring to retain said member in clamped condition, a second member connected with said clamping member, and an adjustably mounted releasing member in the path of said second member to effect the release of said clamping member while the needle bar is passing over dead center at the end of its upward stroke.

8. In an embroidering machine, a needle bar and its actuating means, a drive shaft for said means, a compound cam on said drive shaft, a rectilinear movable yarn clamp controlled by said cam, a loop retaining hook oscillated by said cam, and yarn clamping means having releasing devices to release the yarn during the travel of the needle bar.

9. In an embroidering machine, a support, a work carrying table rotatable therein, means to lock said table with respect to said support, a stationary member on which said support is movable, and having spaced pins, and a manually actuated star wheel cooperating with said pins to effect the longitudinal feed of said support.

10. In an embroidering machine, a drive shaft, a cam on said shaft, a slide reciprocated by said cam and having means to receive a working tool, and a loop retaining hook actuated by said cam.

11. In an embroidering machine, a needle bar and its needle, means to reciprocate said needle bar, yarn clamping means having a block carried by the needle bar and having a clamping member to clamp the yarn against the block during the reciprocation of said needle bar, and means to release said clamping member as it approaches the limit of its upward stroke.

CHARLES A. KAISER.
